CLAIM

We claim the ornamental design for an open tray with riser and guide panels, as substantially shown and described.

DESCRIPTION

FIG. 1 is a front perspective view of an open tray with a riser and guide panels.

FIG. 2 is a front elevational view of the open tray shown in FIG. 1.

FIG. 3 is a rear elevational view of the open tray shown in FIG. 1.

FIG. 4 is a right side elevational view of the open tray shown in FIG. 1.

FIG. 5 is a left side elevational view of the open tray shown in FIG. 1.

FIG. 6 is a top view of the open tray shown in FIG. 1; and, FIG. 7 is a bottom view of the open tray in FIG. 1.

Features disclaimed with broken lines in the Figures indicate structure which forms no part of the claim. The boundary line surrounding the large unshaded portion in FIG. 7 represents a boundary of the claim with the unshaded portion forming no part of the claim.

FIG. 1-7 are various views of an open tray with a riser and guide panels in accordance with the present design. The guide panel are arranged to cooperate with the riser to retain products in a stacked and staggered configuration.
